(57) **CLAIM**

The ornamental design for a slider for hand-held grater, as shown and described.

DESCRIPTION

FIG. 1 is a top, front and right side perspective view of a slider for hand-held grater showing my new design;

FIG. 2 is a front elevation view, the rear elevation being identical thereto;

FIG. 3 is a right side elevation view, the left side being identical thereto;

FIG. 4 is a top plan view thereof;

FIG. 5 is a bottom plan view thereof;

FIG. 6 is a bottom, rear and right side perspective view thereof; and,

FIG. 7 is an exploded view of the slider for hand-held grater shown in FIG. 1.
